CLAIM

The ornamental design for the “apparatus for gas delivery,” as shown and described.

DESCRIPTION

FIG. 1 is a perspective view of an apparatus for gas delivery, showing my new design;

FIG. 2 is a top plan view thereof;

FIG. 3 is a front elevation view thereof;

FIG. 4 is a rear elevation view thereof;

FIG. 5 is a right side elevation thereof;

FIG. 6 is a left side elevation thereof; and,

FIG. 7 is a bottom plan view thereof.

The broken lines showing unclaimed portions of the apparatus for gas delivery forms no part of the claimed design.
